QUILTED COAT

Eddie Bauer, 417 E. Pine, Seattle, Wash.

Filed Aug. 21, Ser. No. 66,426

Term of patent 14 years

(Cl. D3—4)

FIG. 1

FIG. 2

FIG. 1 is a front view of a quilted coat showing my new design; and

The characteristic features of my design reside in the combination on the coat disclosed of the specific small diamond quilted pattern on the front shoulder portions in association with the larger diamond shaped quilted pattern therebelow, said larger pattern extending around the sides and over the back all as shown.

I claim:

The ornamental design for a quilted coat, as shown and described.
